UNITED STATES PATENT OFFICE

116,836

DESIGN FOR A BATHTUB

James M. Bonner, Los Angeles, Calif.

Application August 1, 1938, Serial No. 79,003

Term of patent 14 years

To all whom it may concern:

Be it known that I, James M. Bonner, a citizen of the United States, residing at Los Angeles, in the county of Los Angeles, State of California, have invented a new, original, and ornamental Design for a Bathtub, of which the following is a specification, reference being had to the accompanying drawing, forming a part hereof.

I claim:

The ornamental design for a bathtub, as shown.

JAMES M. BONNER.
